UNITED STATES PATENT OFFICE.

ALBIN RAVAUTTE, OF MARSEILLE, FRANCE, ASSIGNOR TO ALBIN RAVAUTTE, OF MARSEILLE, FRANCE, EMILE CHARLES ALBERT FLEURENT, OF PARIS, FRANCE, AND SOCIETE ANONYME DES ETABLISSEMENTS EGROT, OF PARIS, FRANCE, A CORPORATION OF FRANCE.

VACUUM DRYING APPARATUS.

1,100,028.

Specification of Letters Patent. Patented June 16, 1914.

Application filed February 24, 1912. Serial No. 679,543.

To all whom it may concern:

Be it known that I, ALBIN RAVAUTTE, citizen of the French Republic, residing at Marseille, Department of the Bouches du Rhône, 5 in France, have invented certain new and useful Improvements in and Relating to Vacuum Drying Apparatus; and I do hereby declare the following to be a full, clear, and exact description of the invention, such as 10 will enable others skilled in the art to which it appertains to make and use the same.

The invention has for its object the construction of an apparatus designed to carry out in a continuous manner, and in an atmosphere 15 maintained at a pressure below that of the atmosphere, the partial or complete desiccation of substances in a pulverulent condition or in small particles.

The apparatus comprises a chamber at 20 the lower part of which is arranged a coiled pipe which serves to heat the substances under treatment and at the same time to displace them with a slow and uninterrupted movement. The chamber is connected to a 25 vacuum pump in such a manner that the water vapor will be exhausted and the air which is withdrawn passes before issuing from the chamber, into a rotating filter which stops the particles of powder. The 30 operation being carried out at a temperature which is not very high, is particularly adapted for the treatment of cereals, of leguminous bodies and their derivatives, flours, meals, groats and the like.

35 In the accompanying drawings: Figure 1 is an end view of an apparatus constructed according to the invention: Fig. 2 is a longitudinal sectional view of the same: Fig. 3 is a sectional view perpendicular to the plane of Fig. 2: Fig. 4 is a similar sectional view, the cleaning apparatus being supposed to be removed: Fig. 5 is a sectional view of a rotary valve having two cells: Fig. 6 shows a longitudinal section of the 40 preceding figure: Figs. 7 and 8 are views similar to Figs. 5 and 6 respectively of a rotary valve having a single cell.

45 Referring to Figs. 1 to 4 the apparatus consists essentially of a drying chamber Y surrounded by a steam jacket Z. At the lower part of the chamber Z are arranged 50 heating pipes 21. At the lower part of the drying chamber is arranged a spirally coiled

pipe 22 fixed on a rotating frame 24. The coiled pipe communicates with the hollow 55 axle 25 the ends of which are mounted in two boxes A and B communicating with the steam chamber Z. The tightness of the joints is obtained by the use of suitable stuffing boxes. On the frame 24 are placed 60 small rubbers or brushes 26 inclined to the axis and arranged in such a manner as to sweep the whole length of the chamber. These small rubbers or brushes serve, together with the coiled pipe, to carry the material from one end of the chamber to the other. The frame 24 receives a rotatory movement from a shaft 15 by means of a chain passing over sprocket wheels 16 and 17. This shaft is itself driven by gears 70 from a motor shaft 1. The upper part of the drying chamber contains a rotary filter W made in the following manner: Upon a perforated tube C are fixed two star-like cheeks D. The peripheries of these two 75 cheeks serve as a support for perforated plates E; a wire gauze applied to the external surface of the plates E completes the body of the filter. It is upon this wire gauze that the filtering cloth, properly so-called, is applied. The central tube C opens at one of its ends into a chamber F. It is closed at the other end by a plate H fixed upon the axis of the cheeks D. The tube C is fixed to a shaft I which receives rotary 80 movement from a shaft 7 by means of a worm wheel 20 actuated by a worm driven by wheels 18 and 19. The shaft 7 on which the chain wheel 18 is secured is actuated by the motor shaft 1. In the interior of the 90 tube C is placed a helical strip O. The chamber F is closed externally by a movable cover upon which is fixed a trough J of semi-cylindrical form. Said chamber is further provided at its upper part with a 95 neck Q in connection with a condenser and exhauster, and with a semi-circular baffle R, this latter producing a lengthened path favorable to the deposit of the dusty particles.

100 The continuous cleansing of the filter tissue is obtained in the following manner: Pins K fixed on one of the wheels H make contact with a finger L which, during rotation of the filter rotates the shafts M and 105 N at the same time straining the opposing

springs V. The shafts M and N carry at intervals along their length small flexible straps or tapping elements P. As soon as, by the rotation of the filter, one of the pins 5 K has left the finger L, the shafts M and N, returned to their position of rest by the spring V, impress a jerking movement upon the straps P which are caused to strike simultaneously the one set on the right hand 10 side and the other set on the left hand side of one of the branches of the filter; the two faces of the same branch of the star are thus struck at each revolution of the filter. The particles shaken off fall back directly into 15 the lower part of the drying chamber Y. The particles which may have traversed the filtering cloth fall back into the trough J, and are carried by the helical strip O into the lower part of the chamber F from whence they can be extracted by removing 20 the plug X.

The apparatus comprises two rotary valves, the ports and over-lappings of which are constructed in such a manner as to shut 25 off all direct communication of the interior of the drying chamber with the outer air.

In Fig. 2 are illustrated valves having one cell; these valves are represented on a larger scale in Figs. 7 and 8. The rotary part is 30 arranged in a fixed casing having two openings, the one 30 for charging and the other 31 for discharging. The rotary portion has trunnions 33 and 34 supported in bearings arranged on the ends of the fixed casing. 35 One of these trunnions 34 is furnished with a device for transmitting to it a rotary movement, the other 33 carries a cross-piece T which can be displaced laterally so as to give an axial movement to the rotary valve. This 40 displacement, obtained by means of the nuts 32 on two screwed rods fixed on the end of the covering casing, enables the valve to be slackened or tightened in position in the casing.

45 The operation of the device is very simple and is as follows: When the valve has thrown the substances which filled it into the chamber, its pocket only contains the rarefied gases and vapors from the desiccation chamber. As soon as the opening of the pocket is again presented below the supply conduit or hopper, the material is forced 50 by the atmospheric pressure into the pocket. The discharge valve has an analogous construction: This casing however has a passage 55 28 opening into the chamber Y. The pocket is thus placed in communication with this chamber before the valve has resumed its charging position. When it arrives in this 60 position equilibrium of pressure is established and the material falls into the interior under the influence of gravity. Several valves for the supply and the discharge can be employed upon one and the same apparatus.

Figs. 5 and 6 show a valve analogous to that described above but having two pockets. At each rotation there will thus be two charges and two discharges. Outside of the pockets the two valves have circular external channels and longitudinal recesses 29 for avoiding heating by a free circulation of air as is shown also in Fig. 7; with the same object the external casing has lateral extensions for radiating heat (Figs. 7 and 8) 75 or is surrounded by a water jacket 35 in which the water is circulated (Figs. 5 and 6). For the discharge valves an equilibrium passage 28 is provided as described above. The drying chamber is maintained at a suitable temperature by means of the steam jacket Z. The external casing has at its upper part a steam gage a safety valve and a pipe U which connects it to the air pump or 80 exhauster. The vacuum having been established in the chamber Z and consequently 85 in the rotary coiled pipe, in its axle and in the boxes A and B, saturated steam at a temperature below 100° can be maintained at will in these spaces; according as the 90 pressure is below or above atmospheric pressure. The heating apparatus 21, placed at the lower part of the chamber Z, forming a 95 boiler is traversed by a hot fluid; steam, water or gas, which produces the evaporation of the water. The water condensed in the rotary coil pipe is extracted at each revolution by the rotation of the helix and re-enters at B into the steam chamber. The 100 condensation produced on the walls of the drying chamber drops directly into the same chamber. Instead of giving to the lower part of the steam chamber the volume necessary for containing the water and the heating apparatus, this part can be reduced and 105 a separate boiler can be employed provided with large tubes communicating with the chamber. The driving gear of the distributors comprises wheels 4 and 5 driven by the shaft 1 and which also drive the shafts 110 6 and 7. The wheels 5 and 8 on said shafts by means of the rods 9 and 10 communicate an oscillating movement to the pulleys 11 and 12. By means of connections jointed or 115 flexible (chains, metallic cables or strips) 115 and fixed at their ends at a point of the rim, the pulleys 11 and 12 act upon the two pulleys 13 and 14 which are keyed on the axles of the valves. In case valves having two 120 cells are employed as represented in Figs. 5 and 6, these rotate with a continuous movement and may be driven directly from the shafts 6 and 7 by means of chains or pulleys. After filtration the gases and vapors 125 are discharged to the vacuum chamber of the condensing apparatus which can be of any kind ordinarily employed.

It is evident that the invention is not strictly limited to the forms of execution indicated above. For instance, a filter can 130

be employed having a different form from that shown, or this device can in certain cases be dispensed with.

I claim:

5 1. A vacuum drying apparatus for the continuous desiccation of pulverulent materials comprising a drying chamber, a steam jacket surrounding the same, a rotatable coiled pipe in said chamber, said pipe being 10 in communication with said steam jacket, and means to rotate said pipe.

15 2. A vacuum drying apparatus for the continuous desiccation of pulverulent materials comprising a drying chamber provided with an exit for the gases or vapors, a rotatable coiled heating pipe in one portion of said chamber, and a filtering device disposed between said heating pipe and said exit and which the gases are caused to pass 20 before reaching said exit.

25 3. A vacuum drying apparatus comprising a drying chamber provided with an exit for the gases or vapors, means to agitate the material in the drying chamber, a filtering

device disposed between said means and said exit and through which the gases are caused to pass before reaching said exit, and means to dislodge adhering material from said filtering device and return the same to the drying chamber.

30 4. In a drying apparatus, a hopper comprising a rotary portion provided with a pocket, a casing surrounding said rotary portion provided with an inlet communicating with the drying apparatus to introduce 35 the material to said pocket and an outlet through which material is discharged from the pocket when said rotary portion is turned in the casing, and means to equalize the pressure in said pocket and drying apparatus before the pocket is in position to receive material from the drying apparatus.

35 In testimony whereof I affix my signature, in presence of two witnesses.

ALBIN RAVAUTTE.
